UNITED STATES PATENT OFFICE.

WILLIAM BEARD LAKE, OF BRAINTREE, ENGLAND.

LIFTING JACK.

Application filed September 8, 1926, Serial No. 134,227, and in Great Britain August 24, 1926.

This invention relates to improvements in lifting jacks and more particularly to hydraulic lifting jacks.

The chief object of this invention is to provide a lifting jack of the hydraulic type with telescopic members and packings therefor which are so arranged that leakage will be positively prevented and the maximum lift be obtained.

Heretofore in hydraulic lifting jacks it has been impossible either to obtain sufficient lift or to prevent the leakage of oil, and consequently such jacks cannot be employed, for instance in a garage, when it is desired to keep the car raised off its tires for a considerable time, as leakage would have the effect of gradually lowering the vehicle.

It is with the object of eliminating this defect that the improved telescopic lifting arrangement and the packing according to present invention are designed.

A further object is to provide means for supporting the leather packing, such means being of a somewhat resilient nature and adapted to prevent the percolation of the liquid through the leather.

With these and other objects in view the invention consists in arranging leather packings of improved shape and in arranging in contact with the packing, a wax or other like substance which is adapted to prevent leakage through the leather packing.

The invention further consists in providing means whereby the hydraulic pressure will assist in maintaining the packing leathers in contact with the surfaces to be rendered fluid-tight.

The invention is still further characterized in that a cylinder containing the telescopic members is fitted with packing to seal the joint between the cylinder and the outer telescopic member and that the inner telescopic member is fitted with a packing to seal the joint between the telescopic members.

The invention still further consists in providing a hydraulic jack having a cylinder adapted to receive a pair of telescopic members, said casing having packing adapted to seal the joint between the casing and the outer telescopic member, and the inner telescopic member having packing to seal the joint between the pair of telescopic members, the arrangement being such that a greater increase in the lifting height can be obtained than heretofore. Further, co-operating

means are provided to limit the upward movement of the telescopic members.

The invention will now be described with reference to the accompanying drawings, in which:—

Figure 1 is a longitudinal sectional elevation of one form of telescopic lifting jack constructed according to this invention and suitable for garage use;

Figure 2 is a sectional plan thereof;

Figure 3 is a cross-section taken on the line *a—a* of Figure 1;

Figure 4 is a cross-section taken on the line *b—b* of Figure 1;

Figure 5 is an enlarged sectional elevation of the upper portion of the jack casing showing the lower end of one of the plungers therein;

Figure 6 is an enlarged sectional elevation showing the co-operating means of the inner and outer plungers;

Figure 7 is an enlarged longitudinal sectional elevation of the valve and plunger, showing the plunger in use, the valve being in position for the lifting operation;

Figure 8 is a similar view to Figure 7 showing the valve operating means in use during the lowering operation;

Figure 9 is a sectional elevation of a modified form of hydraulic jack, suitable for ordinary use and for carrying on a car;

Figure 10 is a plan thereof;

Figure 11 is a cross-section taken on the line *c—c* of Figure 9;

Figure 12 is a perspective view of one end of the jack operating handle for use with the jack shown in Figures 9 and 10;

Figure 13 is a perspective view of the outer end of the plunger rod, and

Figure 14 is a sectional elevation of a portion of a telescopic lifting jack showing an improved form of packing.

As shown, more particularly in Figures 1 to 8, a pair of telescopic plunger members 1 and 2 are mounted in a cylinder 3 formed in a casing 4 which contains an oil or like reservoir 45 from which oil is adapted to pass to the cylinder 3 by way of a valve 6. The casing 4 is provided with wheels 7 which are rotatably mounted and carried by a bracket 8 preferably formed integrally with the said casing 4. To the side of the casing 4 are pivotally mounted at 9 a pair of bracket-like supports 10 which are maintained in their adjusted position by springs or the like 11. In Figure 2 one bracket 10 is shown

in its outwardly extended position and the other bracket 10 is shown folded back on the casing 4 so that the jack can be positioned adjacent to the wheel of the vehicle it is desired to lift. Within the casing 4 is mounted a tubular member 12. This tubular member 12 is adapted to screw into a sleeve or the like 13 which carries the valve 6. This sleeve or the like 13 is mounted in a bore formed in an extension 14 of the wall of the cylinder 3. The valve end of the sleeve 13 is positioned within an enlarged bore arranged adjacent to the lower end of the cylinder 3 and is threaded for the reception of a threaded closure member 15 which is formed with apertures 16. This closure member 15 is adapted to form an adjustable abutment for a spring 17 which is adapted to act on the valve 6 and maintain it on its seating. A suitable 20 gauze screen is positioned in front of the apertures 16 of the member 15. The stem 18 of the valve 6 is preferably of triangular shape and is adapted to move in a circular bore to permit of the ingress and egress of oil. The valve 6 is preferably fitted or provided with a washer. Radially arranged apertures 19 are also provided in the sleeve 13 for the passage of the oil. A portion of the enlarged bore of the sleeve 13 is screw-threaded at 20 for the reception of the threaded end 21 of a rod 22. The threaded end 21 is formed with a slot 23 to permit of the passage of the oil and a screen 24 of gauze or other suitable material is positioned adjacent to the threaded extension 21 to prevent the entrance of dirt. The rod 22 is of square or other angular shape in cross-section and is adapted to project within a similar shaped bore 25 formed in a plunger rod 26 which is adapted to reciprocate and rotate within the tubular member 12. This tubular member 12 is formed with a flange 27 which is arranged within a gland 28 threadedly mounted in the casing 4. On the flange 27 is arranged a cup-leather or like washer 29 and on this washer 29 is mounted a metal washer 30. The arrangement is such that leakage of oil will be prevented during the forward movement of the plunger 26. On 50 the washer 30 is adapted to seat one end of a spring 31 which has its other end seated in a V-shaped washer 32 and abutting upon this washer 32 is a metal washer 33 which is adapted to bear against another cup-leather washer 34 mounted in the gland 28. This latter washer 34 is adapted to prevent the intake of air during the movement of the plunger 26. The gland 28 is formed with apertures 35 to permit of the passage of oil 60 from the oil reservoir 5. This reservoir 5 is adapted to be filled with oil through the apertures in the casing 4. This aperture is closed by a screw-threaded cap 36 formed with an air vent or the like 37. The lower end of the plunger 1 is fitted with a cup-

leather washer or the like 38 which is maintained in position by a nut member or the like 39 screwed on to a threaded extension of the plunger 1. Adjacent to the lower end of the plunger 1 is cut a groove 40 within 70 which is arranged a split expansion ring 41. When the plunger 1 is in its highest position, this ring 41 expands and enters an annular groove 42 cut in the outer plunger member 2 and it will be seen that this arrangement prevents the member 1 from being forced out of the plunger member 2. The lower wall of the annular groove 42 is cut away or inclined at 43 so as to contract the expansion ring 41 and permit the downward 80 movement of the plunger 1 when the weight carried by the crutch head 44 is lowered. The crutch head 44 is preferably adjustably mounted in the plunger 1 in the well-known manner, the adjustment being effected by 85 means of a pin 45 adapted to be positioned in one of a plurality of apertures 46 formed in a rod 47 carried by the crutch head 44, the pin 45 being arranged transversely and adapted to seat on the upper end of the plunger 1. 90 A suitable washer 48 is arranged on the upper end of the plunger 2 to further prevent leakage between the plungers 1 and 2. The lower end of the plunger member 2 is also formed with an annular groove 49 which is cut away 95 or inclined at 50 in a similar manner to the groove 42. Within this groove 49 is adapted to be positioned a split ring 51 when the plunger 2 is in its highest position and thus limit the outward movement of the plunger 100 2. The split ring 51 is normally arranged within a groove 52 cut in the cylinder 3 and the arrangement is such that the split ring 51 will be expanded and lie in the groove 52 when the plunger 2 is lowered by the 105 weight carried by the crutch head 44. The upper end of the cylinder 3 is maintained oil-tight by washers 53 and a threaded member 54 screwed into the said upper end of the cylinder 3. An oil leak 55 is provided 110 for the return of any oil to the reservoir 5 which may have passed by the lower washer 53. Thus it will be seen that by arranging the packing washers in the casing 3 and in the inner telescopic member 1, the said telescopic members may be raised to a maximum height to give considerably greater lift than heretofore. 115

To the outer end of the plunger rod 26 is pivoted at 56 a connecting rod member 57 which is pivotally mounted in any suitable manner in the lower forked end 58 of an operating lever 59 which is fulcrumed on a fulcrum pin 60. This fulcrum pin 60 is carried in a forked bracket 61 which is adapted to 120 form a base for the operating lever 59. This forked bracket 61 is also secured to the outer end of a member 62 which is connected at its other end to the casing 4; thus the fulcrum portion of the jack is maintained rigidly in 130

spaced relation to the casing portion of the jack. The lever 59 is preferably provided with an auxiliary fulcrum 63 and is so arranged that it may be adjusted in an angular position, for instance, the lever 59 may be arranged in its normally vertical position by placing a pin 64 through an aperture 65 cut in a plate 66 carried by the forked end 58 or it may be arranged in an angular normally inclined position by placing the pin 64 through the aperture in the lever 59 and through an aperture 67 in the plate 66, when it is inconvenient for the lever 59 to be in a normally vertical position, such as when the jack has to be positioned a considerable distance under the car. The upward movement of the lever 59 is limited by a plate 68 secured to the forked bracket 61 and adapted to engage the forked end 58 of the operating lever 59. To the outer end of the connecting rod member 57 is secured a handle member 69 whereby the plunger rod 26 may be rotated in the manner to be hereinafter described. The outer end of the connecting rod 57 is rotatably mounted in the forked end 58 of the operating lever 59 through the medium of a pair of nut members 70.

In operation, and assuming that the jack is in its lowest position with the crutch head 44 positioned under, for instance, an axle of a vehicle, it is desired to lift and the operating lever 59 is in a vertical position, the said lever 59 is moved downwardly to force the plunger 26 into the tubular member 12. It will be obvious that by reciprocating the plunger 26 through the medium of the operating lever 59 oil from the reservoir 5 will be forced past the valve 6 into the cylinder 3 by way of the aperture 23 in the threaded member 21 and apertures 19 in the sleeve 13. During this operation the oil will be drawn in from the reservoir 5 by way of the ports 35 and will be forced into the cylinder 3 to raise the plungers 1 and 2 and the crutch head 44. When the plungers are fully raised the split ring 41 in the plunger 1 will expand and enter the annular groove 42 cut in the outer plunger 2 and the split ring 51 normally positioned in the groove 52 of the cylinder 3 will contract and enter the groove 49 cut in the outer plunger 2. When it is desired to lower the jack the operating lever 59 is returned to its normal vertical position and the handle member 69 is turned to partially rotate the plunger 26. This partial rotation of the plunger 26 will also rotate the rod 22 and turn the threaded end 21 in the sleeve 13 and thus the forward end of the rod 22 will engage on the valve stem 18 and force the valve 6 off its seating against the action of the spring 17. The oil in the cylinder 3 will now return by way of the ports 23 and 35 and the tubular member 12 to the reservoir 5. The lowering speed of the jack can be varied according to the amount the valve 6 is moved

off its seating and the lowering will be assisted by the weight carried by the crutch head 44. When the lowering operation is completed the handle 69 is turned back to its normal position so as to permit the valve 6 to function in the usual manner. The first outward or downward movement of the operating lever 59 will obviously create a vacuum in the tubular member 12 until the oil can flow from the reservoir 5 through the port 35. The forward movement of the plunger will force the oil past the valve 6 into the cylinder 3 and the sequence of operations will be repeated when it is required to again use the jack. The wheels 7 on the forward end of the jack will assist the positioning of the jack under the car and it will be seen that the jack will be adequately supported when one or both of the brackets 10 are in their outward position.

In a modified construction as shown in Figures 9 to 13, and when the invention is applied to a jack suitable for ordinary use and for carrying on a car, the casing 4 is formed with a bifurcated bracket 71 which is adapted to carry a fulcrum pin 72 on which is mounted a handle socket 73. This operating handle socket 73 is formed with a pair of downwardly extending arms 74 on which are mounted one end of connecting links 75. The other ends of the connecting links 75 are connected to a sleeve 76 which is mounted on the outer end of the plunger rod 26 which is adapted to reciprocate within the casing 4 and operate in a similar manner to that previously described. The casing portion 4 of the jack and the plunger members 1 and 2 will not be further described as the construction and operation is similar to the previous construction. Within the socket 73 is adapted to be placed the lower end of an operating handle 77 of any suitable length. The lower end operating handle or lever 77 is formed or provided with a bayonet joint or fitting 78 which is adapted to co-operate with a bayonet fitting 79 formed or provided in the interior of the socket 73. The arrangement is such that when the handle 77 is forced into the socket 73 and given a partial rotation, the said handle 77 will be detachably locked in position in the co-operating bayonet fittings by the action of a spring 80 disposed within a recess formed in the lower end of the said socket 73. The extreme lower end of the handle or lever 77 is formed with another bayonet socket fitting 81 which is adapted to co-operate with a socket pin fitting 82 secured on the outer end of the plunger rod 26.

In operation, and when it is desired to raise this modified form of jack, the casing 4 is positioned under the vehicle and the crutch head 44 is arranged under the portion of the vehicle to be lifted. The operating handle lever 77 is pushed into the handle socket 73 against the action of a spring 80

and partially rotated so that the bayonet fittings 78 and 79 co-operate to hold the handle 77 in position. Upon the downward and upward movement of the handle 77 the 5 plunger 26 will be reciprocated through the medium of the links 75 and arms 74 and thus the oil will be forced from the reservoir 5 past the valve 6 into the cylinder 3 to raise the plunger members 1 and 2 in a manner 10 similar to that described in the previous construction. A suitable stop 83 is provided on the bracket 71 to co-operate with a squared end 84 formed on the socket 73 and thus limit the upward movement of the handle or lever 15 77. When it is desired to lower the jack the handle lever 77 is forced inwardly against the action of the spring 80 and partially rotated to unlock the co-operating fittings 78 and 79 and permit of the withdrawal of 20 the said handle. The extreme lower end of the handle or lever 77 is now inserted in the socket pin fitting 82 on the plunger rod 26 and partially rotated to rotate the plunger rod 26. This rotation of the plunger rod 26 25 will act in a similar manner to that previously described in connection with the first construction and move the valve 6 off its seating and thus the weight carried by the crutch head 44 will be lowered automatically. In 30 this modified construction, the wheels 7 and supporting brackets 10 are omitted, but it will be understood that they may be provided if desired.

Referring to the modified form of packing 35 shown in Figure 14 of the drawings, it will be seen that the jack casing or cylinder 3 is enlarged at its upper end to receive packing means which are adapted to prevent leakage of fluid past the outer telescopic member or sleeve ram 2 in which is mounted the inner telescopic member or inner ram 1 which is 40 fitted at its lower end with packing means to prevent leakage of fluid between the telescopic members 1 and 2. In a threaded recess 85 formed in the upper end of the cylinder 3 is adapted to screw an upper gland nut 86 which is formed internally with a groove or the like 87 of preferably two depths. In 45 the deeper groove 87 is mounted a leather washer or scraper 88 which is adapted to contact with the sleeve ram 2. Below this upper gland nut 86 is positioned a leather 89 of annular shape and below this support is mounted a hat leather 90 of leather or other 50 suitable material. This hat leather 90 is of substantially L shape in cross-section. Below this hat leather 90 is positioned a lower hat leather support 91. Between the leathers 89 and 90 is disposed an annular sheath of wax 55 or other suitable like material 92 of substantially triangular shape in cross-section, and between the leathers 90 and 91 is disposed another wax annular sheath 93. Below the leather 91 and screwing into the base 60 of the recess 85, is a lower gland nut 94,

which is inclined at its inner edge to permit any leakage of pressure to act on the leather 91 and press the same upwardly. The leather 91 is so shaped and clamped between the gland nuts 86 and 94 that it is adapted to act on the 70 vertical portion of the hat leather 90 and press the same against the sleeve ram 2. A leather seat 95 is provided between the lower gland nut 94 and the base of the recess 85 formed in the casing. The lower surface of 75 the gland nut 94 and the base of the recess 85 are formed with circumferential and oppositely arranged V-shaped grooves or recesses 96 to make a firm seating for the seating leather 95. The lower end of the sleeve 80 ram 2 is formed with an enlarged flange 97 which is adapted to abut against the lower leather seat 95 when the sleeve ram 2 is in its high position. Thus leakage of fluid such as oil which is adapted to raise the rams will 85 be effectively prevented.

The lower end of the inner ram 1 is formed with a threaded extension 98 and on this threaded extension is adapted to screw a ram head 99 which is adapted to retain against 90 the bottom of the inner ram an annular shaped leather washer 100 and a leather cup washer 101, which latter is of L shape in cross-section. Between the ram head 99 and the cup washer 101, which latter is of leather, is positioned a wax proofing sleeve 102 which is adapted to press the cup washer 101 outwardly against the inner wall of the sleeve ram 2. The ram head 99 is formed with apertures 103 through which oil is adapted to pass to the 100 wax sleeve 102, and thus the pressure of the oil will further tend to force the cup leather 101 outwardly.

On the upper end of the sleeve ram 2 is adapted to screw a cap or nut 104 which is 105 preferably formed with a knurled edge 105. This cap 104 is adapted to keep in position on the upper end of the sleeve ram 2 a scraper leather washer 106 and a hat leather washer 107. This hat leather washer 107 is of L 110 shape in cross-section and the groove for the vertical portion of this hat leather washer 107 is extended and enlarged at 108 for the reception of any oil which may leak between the rams 1 and 2. Such leakage of oil will tend 115 to press the vertical portion of the hat leather washer 107 against the inner ram 1. The lower edge of the washer 107 is preferably tapered so as to render the said edge more flexible. The lower edges of the other L shaped washers 90 and 101 may be also tapered for a similar purpose if so desired. It will be seen 120 that the wax proofing is so arranged that it will prevent the oil from percolating through the leather washers. Further, the washers 125 are so shaped and disposed that the internal pressure of the oil will tend to force them in such a manner as to render the joints fluid-tight.

In operation and when oil or other fluid is 130

forced into the cylinder 3 by any suitable means the outer ram 2 will be raised until its flange 97 presses against the lower leather 95. Further pressure of the fluid will move the inner ram 1 upwardly in the outer ram 2 and a suitable stop will be provided to limit the upward movement of the inner ram 1.

It will be seen that by the invention there is provided a hydraulic jack for garage or ordinary use which will have a higher lift than is obtained by hydraulic jacks at present constructed and further the lift may be increased by providing more than two telescopic members.

Reference is made to applicant's co-pending application filed September 7, 1926, Serial No. 134,081, for claims directed to subject-matter specifically described but not claimed herein.

What I claim is:—

1. A lifting jack of the hydraulic type comprising a power cylinder, a single valve located at one side of the cylinder and simultaneously controlling the admission of fluid to and its exhaust from the cylinder, and a pair of telescopic members slidably mounted in the cylinder, said telescopic members in collapsed relation extending to substantially the bottom of the cylinder and below the valve whereby, through the length of such telescopic members thus accommodated, the jack is capable of a minimum height in collapsed relation and a maximum height in extended relation.

2. A lifting jack of the hydraulic type comprising a power cylinder, a single valve located at one side of the cylinder and simultaneously controlling the admission of fluid to and its exhaust from the cylinder, a pair of telescopic members slidably mounted in the cylinder, said telescopic members in collapsed relation extending to substantially the bottom of the cylinder and below the valve, and cooperating means carried by the wall of the cylinder near its upper end and the wall of the outermost telescopic member near its lower end to limit the extended movement of such telescopic member relative to the cylinder.

3. A hydraulic jack including a cylinder formed above its lower end with an opening for the inlet and outlet of the fluid pressure, a single valve for controlling this opening, and a plurality of telescopic members movable in the cylinder, the outermost of such members being in hollow cylindrical form, the unobstructed wall of the fluid cylinder of the jack permitting collapsing movement of

the telescopic cylinder to a position just free of contact with the bottom of the fluid cylinder and past the opening in the wall of the fluid cylinder, whereby to permit of telescopic members of maximum length with minimum projection beyond the fluid cylinder in their telescoped relation to thereby provide a jack having minimum height when collapsed with maximum height when extended.

4. A hydraulic jack having a pressure fluid cylinder formed with a fluid opening, telescopic members movable in the cylinder and relative to each other under fluid pressure, the outermost member being formed near its lower end with an annular groove, and a spring member arranged in the wall of the cylinder near the upper end thereof to engage in said groove to limit the relative outward movement of the telescopic member.

5. A hydraulic jack having a pressure fluid cylinder formed with a fluid opening, telescopic members movable in the cylinder and relative to each other under fluid pressure, the outermost member being formed near its lower end with an annular groove, and a split spring ring mounted in the wall of the cylinder and adapted to engage in said groove to limit the relative outward movement of the telescopic member.

6. A hydraulic jack having a pressure fluid cylinder formed with a fluid opening, telescopic members movable in the cylinder and relative to each other under fluid pressure, the outermost member being formed near its lower end with an annular groove, and a split spring ring mounted in the wall of the cylinder and adapted to engage in said groove to limit the relative outward movement of the telescopic member, said telescopic member being formed to extend the ring into non-active position in the inward movement of the telescopic member.

7. A hydraulic jack having a pressure fluid cylinder formed with a fluid opening, telescopic members movable in the cylinder and relative to each other under fluid pressure, the outermost member being formed near its lower end with an annular groove, a spring member arranged in the wall of the cylinder near the upper end thereof to engage in said groove to limit the relative outward movement of the telescopic member, and packing carried by the cylinder near the outer end thereof to seal the juncture between the cylinder and said outermost telescopic member.

In testimony whereof I have hereunto signed my name.

WILLIAM BEARD LAKE.
